ELECTRICALLY VIBRATABLE HAIR BRUSH

Thomas Kellogg, Mamaroneck, N.Y., assignor, by mesne assignments, to The Songrand Corp., Kansas City, Mo., a corporation of Missouri

Filed Aug. 12, 1963, Ser. No. 76,184

Term of patent 14 years

(Cl. D9—2)

FIGURE 1 is a top view of an electrically vibratable hair brush showing my new design.

FIGURE 2 is a side view thereof.

FIGURE 3 is a bottom view thereof.

FIGURE 4 is a front end view thereof.

FIGURE 5 is a rear end view thereof.

FIG. 6 is a perspective view showing the holder portion removed from the handle portion thereof.

FIG. 7 is a bottom plan view of the holder portion thereof.

The broken line showing of the electric cord shown broken away in FIG. 2 for convenience of illustration is for illustrative purposes only.

I claim:

The ornamental design for an electrically vibratable hair brush, as shown and described.
